US00D528528S

(12) United States Design Patent (10) Patent No.: US D528,528 S
Moon et al. (45) Date of Patent: * Sep. 19, 2006

(54) PORTABLE TELEPHONE

(75) Inventors: Ji-Hyun Moon, Seoul (KR); Beom-ku Han, Seoul (KR); Chang-Hwan Hwang, Seoul (KR)

(73) Assignee: Samsung Electronics Co., Ltd., Kyunggi-do (KR)

() Term: 14 Years

(21) Appl. No.: 29/226,418

(22) Filed: Mar. 29, 2005

(51) LOC (8) Cl. 14-03

(52) U.S. Cl. D14/138

(58) Field of Classification Search D14/137, D14/138, 147-148, 247-248, 144, 496, 156, D14/341-347, 191, 192; 379/433.01-433.13; 455/575.4, 566, 575.1, 556.1, 556.2, 90.3; D21/329, 331, 333, 517; D16/208

See application file for complete search history.

(57) CLAIM

We claim the ornamental design for a portable telephone, as shown and described.

DESCRIPTION

FIG. 1. is a top front perspective view of a portable telephone showing our new design.

FIG. 2. is a front elevational view thereof.

FIG. 3. is a rear elevational view thereof.

FIG. 4. is a left side elevational view thereof.

FIG. 5. is a right side elevational view thereof.

FIG. 6. is a top plan view thereof; and,

FIG. 7. is a bottom plan view thereof.
